UNITED STATES PATENT OFFICE.

ALEXANDER FRANZ PAUL MALIN, OF KAPPEL, GERMANY.

FORGING-MACHINE.

SPECIFICATION forming part of Letters Patent No. 455,598, dated July 7, 1891.

Application filed January 9, 1891. Serial No. 377,232. (No model.)

To all whom it may concern.

Be it known that I, ALEXANDER FRANZ PAUL MALIN, a subject of the King of Saxony, residing at Kappel, Saxony, German Empire, have invented certain new and useful Improvements in Forging-Machines with Continuous Action, of which the following is a description.

The forging-machine forming the subject of my invention is characterized by the arrangement of new and special devices for advancing the iron for flat or plain forging and for cutting off the same, and by these means I not only obtain a considerable saving of time, power, and material, but also of wages for the attendants, as an inexperienced hand may be employed for the operation of the machine.

I have illustrated my new forging-machine in the annexed drawings, which form a part of this specification, and wherein like letters of reference indicate like parts throughout all the figures, old and known parts being omitted for the sake of clearness.

In the drawings, Figure 1 represents a side elevation of a machine, partly in section, in which my improvements are embodied. Fig. 2 is a detail elevation, partly in section, of a portion of the machine shown in Fig. 1. Fig. 3 is a top plan view of Fig. 1. Fig. 4 is an end view of Fig. 3; and Fig. 5 is a detail plan view, partly in section, showing certain features of the machine.

The articles are forged from an endless iron bar *a*, which is wound upon a reel *A*, Figs. 1 and 3, and which is fed to the forging apparatus proper through a heating furnace or hearth *B* by means of an advancing or feeding device specially adapted for this purpose.

The advancing or feeding of the iron band *a*, made white-hot in the furnace or hearth *B*, is effected by jerks, according to the finishing of the parts which are being forged, by means of two pairs of rollers, one pair of which *b b* is arranged directly before the entrance, and the other *b' b'* directly at the opening for the exit of the iron. The upper rollers *b* and *b'* of both pairs are pressed upon the lower rollers by weights *C* or by means of a spring *c*, so that when the lower rollers are rotated the iron will be fed to the forging device with a pressure which can be regu-

lated at will. By this arrangement of the feeding-rollers any danger of upsetting or stretching of the hot iron is avoided, as the front rollers *b b* will feed into the hearth exactly the same length of iron as will be withdrawn from the hearth by the other pair *b' b'*. On the axles of the lower rollers of each pair *b* and *b'* are arranged ratchet-wheels *D* and *D'*, Figs. 1 and 2, and levers *d* and *d'*, Fig. 2, the latter carrying weighted pawls *d² d²*. Both levers *d* and *d'* are jointed to a pushing-rod *E*, which is pivotally connected to a bent lever *e*, which is hinged to the frame at *e'*, and is provided with a friction-roller *e²*, resting on a cam *F* of the forging-shaft *f*.

As the motion of the forging mechanism is likewise derived from the shaft *f* and the forged object is finished during a not entirely accomplished rotation of this shaft, and as, moreover, the forwarding or feeding mechanism is only brought into operation by the cam *F* slightly previous to the accomplishment of the revolution, it is obvious that the iron rod *f* remains in repose during the entire forging process and is only advanced again after it is finished.

The forging mechanism operated by the shaft *f* consists of three parts, viz: first, the roller-disk forging the upper surface of the object; second, the anvil shaping the lower surface of the object, and, third, the side forger consisting of a stationary and a loose plate.

The roller-disk *G*, Figs. 1, 3, and 4, is provided on its circumference with a recess or cut-out part *g*, for the entrance of a circular saw severing the forged object, and it carries at its periphery seven chilled cast-iron rollers *g' g² g³*, &c., steadily increasing in diameter from the first to the last, so that these rollers will finish the upper surface of the object resting on the anvil.

Perpendicularly underneath the forging-shaft *f* is arranged the fixed anvil *H*, in which is formed the mold for the under surface of the object. The roller-disk *G* presses the white-hot iron into the mold of the anvil, forging at the same time the upper surface. The sides of the object are finished by a special device provided for this purpose. This device consists of a rigid and a movable plate, in which the molds for the side surfaces of the object are made. The rigid plate *h*, Fig.

5, is suitably fixed by means of screws and a key, so that one side of the advancing iron bar rests sidewise against it. The loose plate h' is suitably guided in a bed, and is connected 5 to the lever I, to which a swinging motion is imparted, and thus, like a hammer, strikes on the iron bar placed between the two plates h and h' . To obtain this latter result, the lever I, connected to the loose plate h' , is hinged 10 to the frame at I', and is provided opposite the plate h' with a friction-roller i , arranged in a straight line, with a second roller i' fixed to the frame, Fig. 4, a wedge K being arranged between the two rollers. The wedge K rests 15 on a blade-spring k , secured to the framework and also on a guide, and is operated upon from above by a second roller-disk L, containing, similarly to the disk G, rollers l , &c., like the rollers g , g^2 , &c., but not 20 provided with the recess or cut-out part g of disk G. With the rotation of the shaft f the forging-disk G acts upon the upper surface 25 of the object, and the under surface of the same is pressed into the recess arranged in the anvil H. The friction-rollers l , l' , &c., strike at the same time the wedge K and push it down, and as the same is raised immediately after one of the rollers l has passed, by means of the spring k , the lever I, with the 30 plate h' , which is pulled back by the spring n , will thus impart strokes to the iron, and, co-operating with the fixed plate h , will finish the side surfaces of the object. After each 35 stroke of the friction-rollers g , g^2 , &c., one of the rollers l , l' , &c., will strike the wedge K. Thus a side stroke is imparted to the object immediately after each top stroke, and in this manner the object will be uniformly and 40 equally finished after one revolution of the forging-shaft f , without any further assistance being necessary.

After the object is finished in the manner described it is severed from the bar, and this operation is performed just before the bar a is advanced farther. The severing is effected 45 by a circular saw M, Fig. 4. The saw M is loosely carried on the arm m , rigidly connected to the axle o of the gear-wheel O, and this saw is permanently connected to the 50 small gear-wheel n' , engaged with the wheel N, rigidly connected to the bearing of axle o . The axle o is rotated by means of the conical gear-wheels o , o^2 and the cog-wheel o^3 , and thus the arm m will carry the small cog-wheel 55 n' , with the saw M, around the rigid tooth-wheel N. Consequently the saw M describes a circle around the axle o , rotating at the same time on its own axle in accordance with the transmission relations of the wheels N and n' . At the moment that the saw, which 60 is carried around by the lever m and revolving at the same time on its own axle, reaches the plane of rotation of the roller-disk G it will meet there with the recess g . This recess is made so large that the traveling saw 65 will have crossed the plane of rotation of disk G before the recess g will have passed the

way of travel of the saw M. Consequently the saw M will only strike the bar a , and while continuing its travel it will sever the 70 finished object from the bar. The finished object is now ejected by any of the known devices, and the feeding apparatus will advance the hot iron bar for a suitable length under the forging mechanism. 75

Having thus described my invention, what I claim as new, and desire to secure by Letters Patent of the United States, is—

1. In a forging apparatus, the combination, 80 with a reel carrying the iron bar or band from which the articles are to be forged, and a heating-furnace, of a feeding mechanism intermittently operating to draw said bar or band through the furnace, a main driving-shaft provided with a disk equipped with forging-tools to shape the upper surface of the article being forged, an anvil located beneath 85 said disk and having a suitable conformation to give shape to the under surface of the article being forged, a second disk likewise 90 mounted on the main driving-shaft, a pair of plates arranged in a horizontal plane at opposite sides of the anvil and constructed to give shape to the sides of the article being forged, and means coacting with the last-mentioned disk and with one of said plates to cause said plate to produce at suitable intervals hammer-like blows upon the article being forged, substantially as set forth. 95

2. In a forging apparatus, the combination, 100 with a reel carrying the iron bar or band from which the articles are to be forged, and a heating-furnace, of a feeding mechanism intermittently operating to draw said bar or band through the furnace, a main driving-shaft 105 provided with a disk equipped with forging-tools to give shape to the upper surface of the article being forged and having a portion of its circumferential face cut away to permit the entrance of a severing device, an anvil located beneath said disk and having a suitable conformation to give shape to the under surface of the article being forged, a second disk likewise mounted on the main driving-shaft, a pair of plates arranged in a horizontal plane at opposite sides of the anvil and 110 constructed to give shape to the sides of the article being forged, means coacting with the last-mentioned disk and with one of said plates to cause said plate to produce at suitable intervals hammer-like blows upon the article being forged, and a saw in gear with the main driving-shaft and adapted to enter at appropriate intervals the cut-out portion 115 of the first-mentioned disk to sever the finished article from the bar or band of iron, substantially as set forth. 120

3. The combination, with the furnace and the main driving-shaft of the forging apparatus, of a feeding mechanism for advancing 130 the bar or band from which the articles are to be forged, consisting of two pairs of rollers, one pair located in front and the other pair at the rear of the furnace and coupled or

geared together to operate in unison, a lever, as *e*, coacting at one end with the coupling means of the rollers, and a cam mounted on the main driving-shaft of the apparatus and co-operating with said lever, whereby the bar or band is advanced intermittently in a uniform manner and upsetting or stretching of the same is prevented, substantially as set forth.

10 4. The combination, with the main driving-shaft of the forging apparatus, said shaft provided with a cam, as *F*, of two pairs of rollers for feeding the band or bar of iron from which the articles are to be forged, weights or springs for exerting a regulated pressure of the upper rollers on the lower rollers, ratchet-wheels carried by the axles of the lower rollers, levers, as *d*, also affixed at one end to said axles and carrying at their opposite ends weighted pawls 15 coacting with said ratchet-wheels, a rod, as *E*, jointed to levers *d*, and bent lever *e*, hinged to the frame of the apparatus and connected to rod *E* and provided with a friction-roller co-operating with the cam on the main shaft, 20 substantially as set forth.

5. The combination, with the main driving-shaft *F* of the forging apparatus and means for feeding the bar or band from which the articles are to be forged, of a disk, as *L*, carrying a series of rollers, as shown, a stationary anvil furnishing a support for the article being forged, a fixed plate, as *h*, and a suitably-guided movable plate, as *h'*, said plates supported in a horizontal plane and formed to 30 give shape to the sides of the article being forged, a swinging lever, as *I*, connected to said movable plate, friction-rollers, as *i i'*, and a wedge, as *K*, with which the rollers in the periphery of disk *L* co-operate, whereby hammer-like blows are delivered onto the article being forged, substantially as set forth.

6. The combination, with the main driving-shaft *F* of the forging apparatus and means for intermittently feeding the band or bar from which the articles are to be forged, of a disk, as *G*, mounted on shaft *F* and provided

with forging devices in its periphery, a stationary anvil located beneath disk *G* and adapted to forge the under surface of the article and co-operating with disk *G*, a second disk *L*, also mounted on shaft *F*, and carrying a series of rollers in its periphery, and side-forging mechanism consisting of a fixed and a movable plate, the latter carried by a swinging lever, with which disk *L* co-operates to 55 impart the required side blows to the articles being forged immediately following the blows effected by the action of disk *G*, substantially as set forth.

7. The combination, with the main driving-shaft *F* of the forging apparatus and means for intermittently feeding the band or bar from which the articles are to be forged, of a forging-disk, as *G*, provided with a cut-out portion, and a circular saw mounted in proximity to the disk *G* and in gear with the main driving-shaft to cause it to move bodily within a circumscribed circle, while at the same time adapted to constantly rotate on its own axis, whereby each time the forging is effected said saw crosses the plane of rotation of said forging-disk and severs the completed article from the band or bar of iron without loss of material or unshaping of the object, substantially as set forth.

8. The combination, with main shaft *F*, provided with forging-disk *G*, having a cut-out portion, as explained, of circular saw *M*, loosely carried on arm *m*, which latter is rigidly connected to the axle of gear-wheel *O*, 80 small gear *n'*, fixedly connected to said saw, toothed wheel *N*, fixed to the bearing of gear-wheel *O* and co-operating with small gear *n'* and gearing, such as *O' O² O³*, substantially as set forth.

In witness whereof I have hereunto set my hand in presence of two witnesses.
